UNITED STATES PATENT OFFICE

JOSEPH J. EHEMANN, SR., AND BENJAMIN F. SINGER, OF LANCASTER, PENNSYLVANIA

SAFETY DEVICE

Application filed March 23, 1929. Serial No. 349,474.

This invention is a safety device for use upon automobiles and its object is to provide a device which will automatically arrest the movement of the vehicle if it should start to travel backward on a down grade. It is the habit with motorists to take all grades in high gear to avoid the labor of shifting gears and it frequently happens that the machine stalls before the top of the hill has been reached and, unless the chauffeur is adept at shifting gears, the machine will travel backward some little distance before its progress can be stopped. Numerous bad accidents have occurred through the lack of means to instantly stop the rearward travel of the machine, and the object of the present invention specifically stated is to provide means which will automatically operate to prevent reverse travel of the vehicle on a down grade. The invention provides means whereby when the reverse travel of the machine is desired the safety device will be thrown into inoperative position and will then not interfere with the desired travel until the gears have been shifted to again provide for forward travel. The invention is illustrated in the accompanying drawings and will be hereinafter first fully described and then more particularly defined in the appended claims.

30 In the accompanying drawings:

Figure 1 is a sectional elevation of the transmission gearing of an automobile and the cooperating parts showing our present invention embodied therein.

35 Fig. 2 is an enlarged longitudinal section through the safety device.

Figs. 3 and 4 are elevations showing operative and inoperative positions of the device, and

40 Fig. 5 is an enlarged detail perspective view of the hub.

In the drawings, the reference numeral 1 indicates a portion of the motor housing, 2 indicates the transmission gear housing and 3 the usual hand lever controlling the transmission gearing through shifting rods 4 and selector yokes 5. In carrying out the present invention, there is provided a circular case 6 which is secured rigidly to the rear end of

45 the transmission case around the propeller

shaft 7. Keyed to the shaft within the case 6 is a hub 8 which is constructed with a plurality of right angular recesses 9 in its periphery, each of which forms with the annular wall of the case 6 a triangular chamber 10. Disposed within each chamber 10 is a free roller 11 and in the base wall of the right angle is formed a socket 12 receiving a pin 13 which carries a cup 14 at its free end, an expansion spring 15 being disposed around the pin 13 between the base wall 16 and the cup, as shown in Figs. 3 and 4. The cup is adapted to fit close to and press upon the roller 11 so that the spring 15 tends constantly to hold the roller at the point of the triangular chamber 11 and thereby causes the roller to bind between the walls of the chamber and prevent movement of the shaft 7 in one direction. Disposed at the side of the hub are a plurality of cranks 17, each of which carries a fulcrum pin 18 engaged in a socket 119 formed in the hub whereby the crank may rock in the operation of the device. The crank projects over the triangular chamber 10 and at its projecting end is equipped with a pin 19 which is adapted to bear upon the roller 11 in opposition to the cup or presser plate 14 and hold the roller in an inoperative position. At the inner end of the crank is a lug 20 which is adapted to be engaged by the tapered end 21 of a sleeve 22 so that the crank may be rocked and the roller permitted to move to the point of the triangular chamber. The sleeve 22 is provided with an annular groove 23 in its outer end which is engaged by the selector yoke 5 on the shifting rod 4 which controls the reverse gear and normally the sleeve is away from the several lugs 20, as shown in Figs. 1 and 2. To accommodate the several cranks 17, lugs 24 are provided upon the side of the hub 8 and a cap ring 25 is secured upon the case 6 and rests upon these lugs and projects over the several cranks and the rollers to prevent loss of the same.

Ordinarily, when the shaft 7 is rotating to drive the vehicle forward, the speed thereof, through centrifugal action will cause the outer ends of the cranks 17 to swing about their respective pivots 18 and overcome the

force of the springs 15 so that the rollers 11 will be held in retracted position, as shown in Fig. 4. In this position the rollers will be out of contact with at least one wall of the triangular chambers and the forward rotation of the shaft may continue without interruption. Even if the speed should be insufficient to rock the cranks as stated, the rollers would fail to bind. The forward movement of the shaft carries the apexes of the triangular chambers in a direction away from the rollers so that the resistance to the movement of the rollers is removed but reverse movement of the shaft carries the apexes of the chambers toward the rollers and permits the rollers to bind between the opposed converging sides of the recess. When the rotation of the shaft stops, the cranks will swing to the position shown in Fig. 3 and the rollers will be projected toward the points of the respective chambers 11 and, consequently, will bind between the side walls thereof and prevent backward rotation of the shaft. If it be desired to have the machine travel rearwardly, the reverse gear is thrown in in the usual manner and this action causes the sleeve 21 to slide into engagement with the several lugs 20 and bear against the convex inclined surfaces of the same and rock the cranks so that the rollers will be positively held in their retracted positions, as will be understood upon reference to Fig. 4.

From the foregoing description, taken in connection with the accompanying drawings, it will be seen that we have provided a very simple and compact device which may be readily applied to existing automobiles or installed in vehicles now building. The ordinary operation of the automobile will not be affected by the safety device but any attempt of the machine to travel backward, as upon a steep grade which it is desired to ascend, will cause the brake rollers to automatically shift into locking position and stop the rearward travel.

Having thus described the invention, we claim:

1. In a safety device, the combination of a stationary case, a hub rotatable within the case and having a tapered recess in its periphery, a roller disposed freely in said recess, a yieldably mounted presser plate carried by the hub and engaging the roller to hold the same in engagement with the walls of the recess and the case to prevent reverse movement of the hub, a crank pivoted between its ends on an end of the hub, a pin carried by the outer end of the crank and extending within the recess parallel with the axis of the roller, the roller being between the presser and the pin, and means acting on the inner end of the crank to rock the same whereby to overcome the presser and permit reverse movement of the hub.

2. In a safety device, the combination of a

stationary case, a hub rotatable concentrically within the case and having a right angular recess in its periphery forming with the wall of the case a triangular chamber, a roller freely disposed within said chamber, a pin slidably mounted in the base wall of the right angular recess at a right angle to the axis of the roller, a presser plate carried by the pin and having a concave face to engage the roller, an expansion spring acting on the presser plate and disposed between the same and the basal wall, a crank pivotally mounted on an end of the hub, a pin extending from the outer end of the crank into the recess parallel with the axis of the roller at the side thereof opposite the presser plate, a lug on the inner end of the crank projecting therefrom in a direction away from the end of the hub, and means to engage said lug for rocking the crank whereby to hold the roller in opposition to the presser plate.

In testimony whereof we affix our signatures.

JOSEPH J. EHEMANN, Sr.
BENJAMIN F. SINGER.
